UNITED STATES PATENT OFFICE.

SHELDON A. STIENBARGER AND RALPH L. STIENBARGER, OF AUGUSTA, ILLINOIS.

TELEPHONE-TRANSMITTER.

No. 909,702.

Specification of Letters Patent.

Patented Jan. 12, 1909.

Application filed July 16, 1907. Serial No. 384,098.

To all whom it may concern:

Be it known that we, SHELDON A. STIENBARGER and RALPH L. STIENBARGER, citizens of the United States, residing at Augusta, 5 in the county of Hancock and State of Illinois, have invented certain new and useful Improvements in Telephone-Transmitters, of which the following is a specification.

Our invention relates to improvements in 10 telephone transmitters in which it is sought to increase the carrying power of the transmitted current, and also to increase the volume of the sounds transmitted. We attain these objects by the mechanism illustrated in the accompanying drawings in 15 which--

Figure 1 is a side elevation of a telephone transmitter embodying our invention, the mouth piece, front plate and part of the 20 frame of which is shown in cut section. Fig. 2 is similar to Fig. 1, except that it has the frame enlarged to carry duplicate transmission devices. Fig. 3 is a plan of the back electrode A, showing the multiple cells C C. 25 Fig. 4, a side elevation of connecting bolt S, and Fig. 5, a plan of front electrode H showing the means for stiffening same.

Similar letters refer to similar parts throughout the several views.

30 Our invention consists in the novel construction and arrangement of parts as more fully hereinafter described and claimed.

We make the auxiliary diaphragm, which is connected with the main diaphragm, so 35 that it is entirely free to vibrate at all points, that is, being not fastened at the edges, so that the granular material in the multiplicity of cells is equally compressed, whereas in those cases where the diaphragm is 40 practically fast at its edges the central portion vibrates with greater amplitude, thereby compressing the central portion of the granular material more than near the periphery.

45 The action of the secondary or auxiliary diaphragms of our invention is identical to the action of the auxiliary diaphragms of common transmitters except that the provision of multiple cells for carbon granules 50 in our invention multiplies the power of the transmitter to carry or transmit current.

Referring to the drawings, the primary diaphragm is indicated at D and is connected to the secondary diaphragm H, by 55 bolt S, so that any sound that vibrates D,

will be transmitted to H by bolt S, in the manner common to other transmitters.

The secondary diaphragm H may be made of a single piece of any suitable conductor, but as it is very important that it should be 60 as light as possible, we prefer to use a carbon disk C², to which is secured a metallic disk H by soldering, electroplating or other suitable means; and as it is important that the disks H and C² should be quite stiff, we secure this 65 feature by brace ribs B B, secured to H, by soldering or other suitable means.

Frame piece F, is made wide to accommodate the ample front and back electrodes as shown, and when two pairs of electrodes are 70 used it is twice as deep as shown by Fig. 2, and it is provided with cross piece T, to hold the front pair of electrodes by means of tubular bolt J², through which passes bolt S, to which is secured the front one of the back 75 pair of electrodes as shown.

A connecting wire t² connects J and J² with the back electrodes A, and A², as shown; connecting wire t is connected to frame F. 80

The cell openings C. C. in f can be made through a single piece of felt or other suitable non conducting fabric which is secured to the back electrode by any suitable adhesive. 85

We wish it to be distinctly understood that we do not limit ourselves to any particular number of cell openings, nor to the details of construction as these may be changed without departing from the spirit 90 of our invention.

Having described our invention, what we claim as new and wish to secure by Letters Patent is:—

1. In a telephone transmitter, a main diaphragm, an auxiliary diaphragm rigidly secured thereto, said auxiliary diaphragm being bodily movable and practically inflexible, a rear electrode carrying a multiplicity of cells, and granular material within said 100 cells, to be uniformly acted upon by said auxiliary diaphragm.

2. In a telephone transmitter, the combination of a main diaphragm, an auxiliary diaphragm rigidly secured thereto, said auxiliary diaphragm being free to vibrate as a whole, means for rendering such auxiliary diaphragm substantially inflexible, a rear electrode member carrying cells, and granular material within said cells and engaging 110

said auxiliary diaphragm, substantially as described.

3. In a telephone transmitter having an auxiliary or secondary diaphragm combined with multiple cells for carbon granule, the combination therewith of stiffening ribs, substantially as shown and described, and for the purpose specified.

4. In a telephone transmitter having an auxiliary or secondary diaphragm combined

with multiple cells for carbon granule, the combination with the frame thereof of the cross bar T, tubular adjustment bolt J² combined substantially as shown and described and for the purpose specified.

SHELDON A. STIENBARGER.
RALPH L. STIENBARGER.
